UNITED STATES PATENT OFFICE.

ROBERT G. MACKAY, OF CHICAGO, ILLINOIS.

FIREPLACE.

Application filed May 12, 1925. Serial No. 29,810.

This invention relates to fireplaces and has for its primary object to provide a unitary structure of this kind which is capable of being moved from place to place and which 5 can be installed without the aid of highly skilled labor.

Another object of the invention is to provide a fireplace, as characterized, which is formed of plastic material in a suitable 10 mold, and which incorporates a novel arrangement of strengthening and reinforcing means.

A still further object resides in the provision of a unitary fireplace having novel 15 anchoring means for securing the same to a building wall.

A still further object of the invention is to provide a device which will be relatively light in weight by reason of a shell-like wall 20 formation which provides a chamber, at either side of the fire compartment, open at the top and rear and adapted to contain anchoring elements for securing the fireplace to the building wall.

25 The invention further contemplates a unitary fireplace, as set forth, which is neat in appearance, inexpensive of manufacture, and satisfactory in use.

Other objects and advantages will be apparent during the course of the following description.

In the accompanying drawings, forming a part of this specification, and in which like reference characters are employed to designate like parts in all views,

35 Figure 1 is a perspective view of a fireplace constructed in accordance with this invention;

Figure 2 is a fragmentary horizontal sectional view taken on the line 2—2 of Figure 40 1 and showing one of the anchoring means for the fireplace and the containing chamber therefor;

Figure 3 is a section on the line 3—3 of 45 Figure 2;

Figure 4 is an elevation of a reinforcing unit incorporated in the structure; and

50 Figure 5 is a detailed perspective view showing a fireplace wall portion and a novel staple-like element embedded therein for engagement by the anchoring device which secures the fireplace to the building wall.

As shown, the unitary fireplace comprises a relatively light shell-like body of plastic 55 material including end walls 5 and a front wall 6, provided with a medial arched open-

ing 7 extending from its bottom edge and establishing communication with the fire compartment 8. The fire compartment 8 is defined by a back wall 8^a and side walls 8^b 60 which are preferably of fire brick, and a suitable tiled or other hearth 8^c is provided as illustrated. A part of the top 8^d of the fire compartment is shown in Figure 2.

In producing the structure a mold (not 65 shown) is employed and it is preferably formed to give the exterior surface of the walls a brick-like appearance as depicted in Figure 1.

Figure 1 shows that the exterior surface of 70 the front wall is pebbled or otherwise ornamented with particles, as at b, a layer of such being first introduced into the mold. Referring to Figure 2 it is seen that the walls 5, 6 comprise an outer primary layer 75 c of a sand and cement mixture, in the inner surface of which is embedded a section of metal lath 9. Upon the metal lath 9 is disposed the inner layer d of cinder concrete which completes the wall structure. The 80 metal lath section 9 is shaped in front elevation (Figure 3) to conform to the outline of the front wall 6 and is U-shaped as viewed in plan, as suggested in Figure 2, having rearwardly extending legs 9^a at each side. 85 Thus, the one metal lath section serves for a fireplace unit. The object of the metal lath is to reinforce the structure of the device and also to provide for an intimate connection between the layers c and d. 90

As an additional reinforcing means channel bars 10, 11 are employed and may be carried by the inner surface of the lath section 9 as per Figure 3. Channel bar 10 defines a U and skirts just inside the marginal side and top edges of the front wall of the lath section 9 as illustrated. Channel bars 11, two in number, are disposed in horizontally spaced relationship above the archway 7 to reinforce the structure of the fireplace unit at this point, it being noted that their ends extend well beyond the sides of the archway. If not carried by the lath unit 9, channel bars 10, 11 are layed in place thereon preparatory to pouring the cinder 100 concrete into the mold.

While the layers c and d of plastic material are still soft, staple-like elements 12 are inserted through the inner front wall layer d, one at either side of the arch, so that one of their laterally bent inner ends 12^a seats in one of the channel bars 11 against its rear 110

wall as shown in Figure 5. As shown in Figure 2 the bight portions of staples 12 extend beyond the inner surface of front wall 6, in spaced relationship to side walls 5, and 5 receive the ends of links 13. These links 13 are connected by means of a turnbuckle 14 to links 15 which are adapted to be connected as indicated at 16 to the building wall 17 whereby to hold the fireplace unit 10 firmly in position.

The open top of the fireplace is closed by a removable mantel piece 18. When this is taken off the turnbuckles 14 can be conveniently manipulated without necessitating 15 taking out the fire brick 8^a at the side of the fire compartment 8 or cutting through the side wall of the fire compartment in the event that same is also molded. Each anchoring means 12, 13, 14, 15 is therefore 20 housed in a compartment, readily accessible from above by removing the mantel 18,— and also as shown. The same are considerably removed from the fire compartment walls 8^a.

25 A fireplace constructed in accordance with my invention is relatively light, strong and durable and can be shipped from place to place as a unit. By the use of this molded construction a wide variety of decorative effects can be produced which would be impossible in a brick fireplace. Furthermore, 30 a fireplace of this kind will not settle with the chimney. Also in the event that the building has settled the turnbuckles 14 can be adjusted to secure a snug fit again with the adjacent wall.

The cinder concrete *d* being very hard and strong, forming a veritable back bone of the unit and is united with the lighter and 40 more brittle pebble studded layer *c* by the lath section 9. The hardness of the cinder cement assures against chipping with consequent loosening and possible loss of staples 12.

45 Having thus described my invention, what I claim as new and desire to secure by Letters Patent is:

1. A portable fireplace unit of plastic material comprising spaced opposed walls and 50 a front wall connected thereto, a reinforcing element embedded in said front wall, an adjustable anchoring device sustained by said reinforcing element and protruding from the inner face of the front wall at a point spaced 55 from the inner and outer wall, and said anchoring device being adapted for connection to a building wall for anchoring the unit thereto.

2. A portable fireplace unit of plastic material comprising front and end walls, a reinforcing element embedded in said front wall, an adjustable anchoring device sustained by said reinforcing element and protruding from the inner face of the front

wall, and said anchoring device being adapted 65 for connection to a building wall for anchoring the unit thereto.

3. A portable fireplace unit of plastic material comprising front and side walls, the front wall having an opening, a truss bar 70 embedded in said front wall above said opening and having its ends extending beyond the sides of said opening, looped attaching devices embedded in the inner face of said front wall and laterally bent ends engaged 75 behind said truss bar whereby to sustain said looped attaching devices, and adjustable means secured to said looped attaching devices and adapted for engagement with a building wall for anchoring the fireplace 80 unit thereto.

4. A portable fireplace unit comprising a body portion of plastic material having front and side walls, the front wall having an 85 opening therein, a reinforcing unit of metal lath coextensive in area with and embedded in said front wall and having laterally turned end portions embedded in said side walls, a U-shaped reinforcing element embedded in said front wall adjacent said metal lath and having its legs adjacent the plane of said end walls and its horizontal intermediate portion adjacent the upper edge of said front wall, a horizontally disposed 90 truss bar embedded in said front wall above said opening, and between the same and the horizontal portion of said reinforcing element, the ends of said truss bar extending beyond the side walls of said opening 95 to thereby support the wall load above said opening, staple-like elements embedded in the inner face of said front wall, said staple-like elements having laterally bent ends engaging in back of said truss bar, and adjustable connections carried by the bight portions of said staple-like elements and adapted 100 for engagement with an adjacent building wall for anchoring the unit in place.

5. A portable fireplace unit comprising 110 front and side walls, the front wall having an opening; said front and side walls, comprising an outer layer of ornamental plastic material and an inner layer of relatively harder and stronger layer of plastic 115 material forming a backbone or reinforcement for said unit; a metal lath section for uniting said layers, a truss bar embedded in said relatively harder layer and disposed above and extending beyond the sides of said front wall opening adjacent said metal lath section; and support engaging devices extending into said second mentioned layer and having laterally bent ends sustainingly engaged by said truss member whereby to prevent said support engaging devices from 120 pulling out.

In testimony whereof I affix my signature.
ROBERT G. MACKAY.
